LAPEL PIN OR SIMILAR ARTICLE

Donald R. Kilpatrick, 467 Elm Ave., Bogota, N.J.

Filed Aug. 20, 1963, Ser. No. 76,294

Term of patent 14 years

(Cl. D45—19)

Fig. 1.

Fig. 2.

The essential features of my design reside in the full line portions on the drawing and consist primarily in an engraved leaf with a broken cigarette representation superimposed thereon as shown.

I claim:

The ornamental design for a lapel pin or similar article, as shown and described.
